UNITED STATES PATENT OFFICE

139,863

DESIGN FOR AN ADVERTISING SIGN

Rea M. Bruner, Chicago, Ill.

Application September 21, 1944, Serial No. 115,385

Term of patent 7 years

(Cl. D1—12)

To all whom it may concern:

Be it known that I, Rea M. Bruner, a citizen of the United States, residing at Chicago, in the county of Cook and State of Illinois, have invented a new, original, and ornamental Design for Advertising Signs, of which the following is a specification, reference being had to the accompanying drawing, forming part thereof.

Fig. 1 is a front perspective view of an advertising sign, showing my new design; and
Fig. 2 is a rear perspective view.

I claim:

The ornamental design for an advertising sign, as shown.

RE A M. BRUNER.
